Fig. 1.

Fig. 2.

Fig. 5.

*Fig. 4.**Fig. 3.*FIG. 1 is a front perspective view of a vertical record player or similar article, showing my new design;

FIG. 2 is a side elevational view, the opposite side being substantially a mirror image thereof;

FIG. 3 is a front elevational view;

FIG. 4 is a top plan view; and

FIG. 5 is a rear perspective view thereof.

Portions of the drawing figures are lined to indicate contrast in appearance.

The design is characterized by the illustrated relatively shallow rectangular base, by the relatively taller rectangular housing but of narrower depth which rises from the top of said rectangular base at the rear thereof, and by the inclined set-in front wall of the taller housing on which the turntable is disposed nearly vertical.

I claim:

The ornamental design for a vertical record player or similar article, substantially as shown and described.
